BAR STOOL OR THE LIKE

Cecilio I. Lazo De La Vega, P.O. Box 554,
Valdosta, Ga. 31601

Original design application Sept. 7, 1972, Ser. No.
287,035. Divided and this application Apr. 11,
1974, Ser. No. 460,034

Term of patent 14 years

Int. Cl. D6—01

U.S. Cl. D6—32

FIG. 1

FIG. 2

FIG. 3

FIG. 4

FIG. 5

FIG. 1 is a front elevational view of an upholstered bar stool showing my new design;

FIG. 2 is a side elevational view thereof;

FIG. 3 is a rear elevational view thereof;

FIG. 4 is a top plan view thereof; and

FIG. 5 is a bottom view thereof.

I claim:

The ornamental design for a bar stool or the like, substantially as shown and described.
